UNITED STATES PATENT OFFICE

AUGUST MANTEUFFEL, OF CHICAGO, ILLINOIS, ASSIGNOR, BY DIRECT AND MESNE ASSIGNMENTS, OF ONE-THIRD TO AUGUST BLUM, OF CHICAGO, ILLINOIS, AND ONE-THIRD TO ROYAL E. SCHEIDLER, OF CHICAGO, ILLINOIS

CAN PERFORATOR

Application filed August 11, 1930. Serial No. 474,554.

This invention relates to a can perforator, and an object of the invention is the provision of a device simple and durable in construction, economical to manufacture, and efficient in operation, by means of which cans or similar receptacles may be perforated for pouring the contents therefrom. A further object is the provision of a device of this character adapted to be attached to a can or receptacle, and maintained in attached engagement until a can or receptacle has been emptied of its contents, the device being constructed and arranged to seal or close the opening or openings when not in use. As an additional object, the invention contemplates the provision of a liquid receptacle perforating device adapted to perforate both a pouring opening and an air vent opening, with a handle portion, and means for lifting the perforating members out of engagement with the openings when it is desired to pour from the container or receptacle.

Other objects will appear hereinafter.

The invention consists in the combinations and arrangements of parts hereinafter described and claimed.

The invention will be best understood by reference to the accompanying drawings forming a part of this specification, and in which:

Fig. 1 is a side elevational view, partly in section, showing the device in engaged position with a can;

Fig. 2 is a plan view of the device as shown in Fig. 1;

Fig. 3 is a detail perspective view of the pivotally mounted clamping member;

Fig. 4 is a perspective view of the clamping lever;

Fig. 5 is an enlarged detail view showing the perforating arm in depressed position, and the clamping member in disengaged position;

Fig. 6 is a vertical view taken substantially on the line 6-6 of Fig. 5;

Fig. 7 is a view similar to Fig. 5, showing the perforating arm in depressed position, and the clamping member in engaged position; and

Fig. 8 is a perspective view of the support-

ing member and bracket with a portion of the handle.

As illustrated in the drawings, the preferred embodiment of the invention comprises a supporting member or arm 11, which is normally adapted to extend diametrically across the top of a can or similar receptacle. One end of the supporting member 11 is preferably bifurcated to provide a longitudinal slot 12 for the reception or passage of the perforating prong, which shears an outlet opening, and also to provide a pair of depending fingers 13, which engage an edge of the can as shown in Figs. 1 and 2. The remainder of the supporting member 11 is of sufficient length to extend transversely across the entire top of the can, and is then preferably curved downwardly and inwardly to provide a handle portion 14.

A bracket member 15 is mounted upon arm 11, a slightly greater distance from the fingers 13 than the diameter of the can to be engaged, and has integrally formed lateral faces 16, the upper portions of which have circular openings 17 for the reception of a pivot pin 18, and the lower portions of which have rectangular openings 19 for receiving the transverse portion 20 of clamping lever 21. The clamping member 22 is preferably formed of a transverse portion 23 and two substantially parallel side plates 24, each of which is provided with an opening 25 to receive pivot pin 18, and also provided with a clamping jaw 26, which is adapted to engage the downturned flange portion 27 of the can cover as shown in Fig. 7. The side plates 24 are preferably disposed, respectively, adjacent the outer surfaces of the faces 16 of bracket 15, as shown in Fig. 6, and plates 24 are also provided with transversely aligned triangular openings 28, which receive flattened portion 20 of clamping lever 21. As shown in Figs. 5 and 7, the triangular openings cooperate with transverse portion 20 to complete a camming action, whereby when the clamping lever 21 is released or elevated as shown in Fig. 5, clamping member 22 will be withdrawn or disengaged, and when the clamping lever 21 is depressed, clamping member 22 will

100

be shifted into engaged position as shown in Fig. 7.

In addition to slot 12, the supporting member 11 is also provided with a longitudinal slot 29 for the reception of the air vent perforating prong, presently described. The perforating member 30 preferably has two turned ear portions 31, provided with openings for the reception of pivot pin 18, and thus it will be noted that both the clamping member 22 and the perforating member 30 are pivotally mounted upon bracket 15. On the opposite side of pin 18, the member 30 is provided with an upturned or inclined portion 32, which serves as a lifter, and when depressed, elevates member 30 to the dotted line position shown in Fig. 1. Mounted adjacent the free extremity of member 30 is an outlet perforating prong 33, which when forced through the can lid, severs or shears a rectangular opening adjacent the top edge of a can as shown in Fig. 1, in the preferred embodiment disclosed. Mounted adjacent the opposite horizontal portion of member 30 is an air vent perforating prong 34 which, when member 30 is depressed, shears or perforates an air vent opening in the can lid, substantially diametrically opposite to the outlet opening.

As shown in Fig. 7, prong 34 is preferably curved because of its proximity to the pivotal mounting of member 30, and the inner curved portion also serves to crimp the lid inwardly as shown at 35 in Fig. 7. In the full line position shown in Fig. 1, prong 33 extends through slot 12, and prong 34 extends through slot 29. In the preferred embodiment shown, member 30 is normally maintained in depressed position by means of coil spring 36 surrounding pivot pin 18.

The operation of the device is substantially indicated by the foregoing description of parts and functions. To place in operative position, member 30 is elevated by depressing the lifter portion 32, the supporting member 11 is placed transversely of the top of the receptacle, and then lever 21 is swung from the position shown in Fig. 5 to the position shown in Fig. 7, which serves to tightly engage clamping member 22, and consequently the supporting member 11. The perforating member 30 is then manually depressed, during which operation the prongs 34 and 33 shear oppositely disposed openings in the can lid, with the opening cut by prong 33 conveniently located for pouring the contents and the opening cut by prong 34 serving as an air vent. When not in use, member 30 remains depressed with the prongs projecting into the openings so as to exclude air, dust, and other foreign matter. To use, handle 14 is grasped by the hand, lifter portion 32 depressed, and the can tilted to pour the contents through the outlet opening.

Although not necessarily restricted there-

to, the device is especially adapted and is of particular utility in connection with cans of evaporated or condensed milk. In this particular use, the liquid has a tendency to congeal between the edges of the openings and the perforating prongs, so that an air-tight container is provided even after the perforations have been made, and when the device is not in use.

While I have illustrated and described the preferred form of construction for carrying my invention into effect, this is capable of variation and modification, without departing from the spirit of the invention. I, therefore, do not wish to be limited to the precise details of construction set forth, but desire to avail myself of such variations and modifications as come within the scope of the appended claims.

Having thus described my invention, what I claim as new and desire to secure by Letters Patent is:

1. A device for perforating condensed milk cans or the like, comprising a supporting arm arranged to extend transversely across the top of a can, a finger member on said arm for engaging one edge of said can, a bracket member mounted upon said arm adjacent the opposite edge of said can, a clamping member pivotally mounted upon said bracket member and provided with a clamping jaw arranged to engage the adjacent edge of said can, a manually operable clamping lever constructed and arranged to force said clamping member into clamping engagement in one position and to disengage said clamping member in a second position, a perforating member pivotally mounted relative to said arm, and a prong mounted upon said perforating member and arranged when said perforating member is depressed to shear a pouring opening in the top of said can and also normally to close said opening.

2. A device for perforating condensed milk cans or the like, comprising a supporting arm arranged to extend transversely across the top of a can, a finger member on said arm for engaging one edge of said can, a bracket member mounted upon said arm adjacent the opposite edge of said can, a clamping member pivotally mounted upon said bracket member and provided with a clamping jaw arranged to engage the adjacent edge of said can, a manually operable clamping lever constructed and arranged to force said clamping member into clamping engagement in one position and to disengage said clamping member in a second position, a perforating member pivotally mounted relative to said arm, a prong mounted upon said perforating member and arranged when said perforating member is depressed to shear a pouring opening in the top of said can and also normally to close said opening, and a second air vent

prong mounted upon said perforating member and arranged when said perforating member is depressed to shear an air vent opening in the top of said can and also normally to close said opening.

3. A device for perforating condensed milk cans or the like, comprising a supporting arm arranged to extend transversely across the top of a can, a finger member on said arm for engaging one edge of said can, a bracket member mounted upon said arm adjacent the opposite edge of said can, said bracket member provided with transversely aligned openings, a clamping member pivotally mounted upon said bracket member and provided with a clamping jaw arranged to engage the adjacent edge of said can and also provided with transversely aligned openings adapted to register with said bracket member openings, a manually operable clamping lever having a transverse portion arranged to pass through said bracket member openings as well as said clamping member openings to exert a camming action upon said clamping member and force the same into clamping engagement in one position of said lever and to disengage said clamping member in a second position of said lever, a perforating member pivotally mounted relative to said arm, and a prong mounted upon said perforating member and arranged when said perforating member is depressed to shear a pouring opening in the top of said can and also normally to close said opening.
4. A device for perforating condensed milk cans or the like, comprising a supporting arm arranged to extend transversely across the top of a can, a finger member on said arm for engaging one edge of said can, a bracket member mounted upon said arm adjacent the opposite edge of said can, said bracket member provided with transversely aligned openings, a clamping member pivotally mounted upon said bracket member and provided with a clamping jaw arranged to engage the adjacent edge of said can and also provided with transversely aligned openings adapted to register with said bracket member openings, a manually operable clamping lever having a transverse portion arranged to pass through said bracket member openings as well as said clamping member openings to exert a camming action upon said clamping member and force the same into clamping engagement in one position of said lever and to disengage said clamping member in a second position of said lever, a perforating member pivotally mounted relative to said arm, a prong mounted upon said perforating member and arranged when said perforating member is depressed to shear a pouring opening in the top of said can and also normally to close said opening, and a second air vent prong mounted upon said perforating member and arranged when said

perforating member is depressed to shear an air vent opening in the top of said can and also normally to close said opening.

In testimony whereof I have signed my name to this specification.

AUGUST MANTEUFEL.
